UNITED STATES PATENT OFFICE.

LOUIS SCHLESINGER AND LOUIS BOWMANN, OF CHICAGO, ILLINOIS, ASSIGNORS
TO THE CAPITOL MANUFACTURING COMPANY, OF SAME PLACE.

WRENCH.

SPECIFICATION forming part of Letters Patent No. 424,359, dated March 25, 1890.

Application filed December 31, 1889. Serial No. 335,522. (No model.)

To all whom it may concern:

Be it known that we, LOUIS SCHLESINGER, a citizen of the United States, and LOUIS BOWMANN, a subject of the King of Norway, both 5 residing at Chicago, in the county of Cook and State of Illinois, have invented new and useful Improvements in Wrenches, of which the following is a specification.

Our invention relates to that class of 10 wrenches in which a movable jaw is adjusted by a screw swiveled in or tapped through the movable jaw.

It is the purpose of our invention to provide a simple and novel construction whereby 15 the screw shall be relieved from strain, and whereby provision shall be made for the end of the movable screw in the hollow handle of the wrench.

It is our purpose also to provide a simple, 20 novel, and economical construction of the shank and fixed jaw with relation to the handle and movable jaw, whereby a longitudinal space is provided for the adjusting-screw between the parallel bars of the shank, while a 25 recess is formed between said bars and between the plates forming the handle for the reception of the nut.

It is our further purpose to provide a monkey-wrench in which the handle is formed of 30 thin cast-metal plates riveted together upon the lower portions of parallel bars forming the shank of the wrench, whereby great strength and durability are secured with a comparatively small expenditure of metal, 35 the construction being such that an interlocking engagement is made between the parallel bars of the shank and the plates of the handle.

It is our further purpose also to simplify 40 and improve the construction and operation of tools of this class in various details of construction, combination, and arrangement of parts, all of which will be fully set forth hereinafter, and then definitely pointed out in 45 the claims following this specification.

To enable others skilled in the art to practice our said invention, we will describe the same in detail, reference being made to the accompanying drawings, in which—

50 Figure 1 is a side elevation, partly in section, showing our invention. Fig. 2 is a rear

elevation of the parts shown in Fig. 1. Fig. 3 is a transverse section upon the line *w w*, Fig. 1. Fig. 4 is a transverse section on the line *x*, Fig. 1. Fig. 5 is a transverse section 55 on the line *y y*, Fig. 1. Fig. 6 is a plan view of the movable jaw. Fig. 7 is a perspective view of the duplex shank, with one of the plates forming part of the handle.

In the said drawings, the reference numeral 60 1 denotes the fixed jaw of the wrench, which is composed of suitable metal and either formed integral with the duplex shaft 2 or else formed separately and united to said shank. In either case the parallel members 65 of the duplex shank are united at their upper ends by a thick web of metal 3, which underlies the fixed jaw.

The parallel members of the duplex shank are formed with longitudinal channels 4 70 upon or in their opposite faces to diminish the weight without decreasing in any material degree the strength of the shank. The bars 2 are extended or prolonged downward nearly to the point where the handle of the 75 wrench terminates. Throughout that portion over which the movable jaw is adjustable these bars are of increased thickness and channeled at 4, as described; but below this point they are considerably diminished in 80 size and weight to form tangs 6, which constitute the points of support and attachment for the handle. These tangs are each provided with a longitudinal outer rib 7, having parallel straight edges 8 upon its margins, 85 and they are cut away interiorly to form shoulders 9 at the lower ends of the channeled bars 2, for a purpose presently to be described. The ends of these outer ribs 7 are terminated at points somewhat below the 90 shoulders or offsets 9, and the exterior surfaces of the ribs 7 are flush, or nearly so, with the outer faces of the bars 2 of the duplex shank.

The handle of the wrench is composed of 95 two similar metallic plates, or shells 10, each having at one end clasps 12, standing upon each side of a rectangular opening 13, in which the nut is arranged when the parts are assembled. These clasps are formed to swell 100 or diverge upon their outer edges 14, which overlap upon the outer edges of the bars 2,

above the ends of the ribs 7, against which the overlapping portions 14 abut. The straight edges 15 of the plates or shells 10 lie against the ribs 7, with which they form flush exterior faces, the rounded lower ends of the plates being formed with offsets 16, which overlap and abut against the lower ends of the ribs 7 and meet each other in the central plane of the shank.

10 Upon the inner face of each plate 10 is formed a bracket 17, containing a half bearing or guide 18 for the screw by which the movable jaw is adjusted. Nipples 19 also are formed upon the inner faces of the clasps 12 to engage recesses 20 in the lower ends of the bars 2. Upon the lower portion of each plate 10 is formed a boss 21, rising from a transverse bar 22, which spans the space between the tangs 6 and abuts against inner shoulders 22^a upon the lower ends of said tangs.

15 The numeral 23 denotes the movable jaw, which is slipped upon the duplex shank 2. For this purpose it is provided with openings 25 adapted to receive said bars and separated by a transverse integral bar or septum of metal 24. A threaded bar 25 is rigidly united with this jaw and lies between the bars 2 of the duplex shank, its lower end being guided 30 by the bearing-brackets 17. The nut 26, actuating this jaw, lies in the recess immediately below the shoulders 9 and between the clasps 12.

35 The parts forming the handle are united by a rivet 27, passing centrally through the two bosses 21 at the lower end of the handle. Two rivets 28 are also inserted in the upper portion of the handle upon opposite sides of the screw 25, just beneath the bracket 17.

40 The several parts comprising the wrench are cast separately as assembled, fitted, and dressed, the completed article forming a light, cheap, and exceedingly strong wrench. The arrangement of the screw between the members of the duplex shank 2 and the manner of fitting the movable jaw thereon remove the strain almost entirely from the screw, which descends into the hollow handle. We may, however, tap the screw into the movable 45 jaw and swivel it in a suitable manner between the bars of the duplex shank; but we regard the construction shown and described as preferable. We may also cast the rigid jaw and duplex shank in a single piece, or we 50 may form them separately and unite them.

55 Our invention effects a considerable saving in the use of metal, as well as a material economy in the cost of manufacture, and produces a convenient, strong, easily-operated, and 60 highly-ornamented device.

What we claim is—

1. In a wrench, the combination of a stationary jaw having a duplex shank terminating in two separated tangs, a hollow movable 65 jaw adapted to be slipped over the outer ends of the tangs into position on the duplex shank to slide thereupon to and from the stationary

jaw, a handle attached to the tangs below the duplex shank, and an adjustable screw located between the two members of the duplex shank 70 for sliding the movable jaw, substantially as described.

2. In a wrench, the combination of a stationary jaw having a duplex shank terminating in two tangs, a hollow movable jaw adapted 75 to be slipped over the outer ends of the tangs into position on the duplex shank to slide thereupon to and from the stationary jaw, a handle composed of two similar sections screwed to opposite sides of the two tangs, an 80 adjusting-screw located between the two members of the duplex shank for sliding the movable jaw, and a nut bearing against the inner end portions of the handle-sections between said members of the duplex shank, substantially 85 as described.

3. In a wrench, the combination of a stationary jaw having a duplex shank the members whereof are separated from each other and terminate in separate tangs for the attachment of a handle, a movable jaw having two parallel passages separated by a bar and through which the members of the duplex shank respectively pass, and an adjusting-screw interposed between the said members 95 of the duplex shank for sliding the movable jaw on the latter, substantially as described.

4. In a wrench, the combination of a stationary jaw having a duplex shank the members whereof have shoulders or offsets on their 100 inner faces and terminate in two separate tangs, a hollow movable jaw adapted to slip over the outer ends of the tangs into position on the duplex shank to slide thereupon, a handle composed of two independent plates having clasps at their inner or upper ends and secured to opposite sides of the tangs below the shoulders or offsets on the duplex shank, a nut seated between said clasps on the handle-sections, and a screw interposed between 105 the members of the duplex shank for sliding the movable jaw, substantially as described.

5. In a wrench, the combination, with a rigid jaw having a duplex shank, of shells or plates supported by and fastened to tangs 115 upon the bars of the duplex shank, said plates having overlapping portions at each end abutting against the ends of exterior ribs on said tangs and having their edges flush with said ribs, each plate being provided 120 with interior transverse bars spanning the space between the tangs and engaging inner shoulders on the lower ends of the tangs, substantially as described.

6. In a wrench, the combination, with a 125 rigid jaw having a duplex shank the parallel members or parts of which are provided with ribs and tangs at their lower ends, of similar plates or shells mounted upon opposite sides of said tangs, their edges flush with the ribs 130 thereon and their ends having overlapping and meeting portions, a movable jaw having a screw lying between the parallel parts of the shank and guided by meeting brackets

formed on the interior faces of said plates, and a nut lying in rectangular recesses in the upper ends of said plates and beneath shoulders formed on the inner faces of the members of the shank, said plates being united by rivets, substantially as described.

7. In a wrench, the combination, with a duplex shank composed of parallel bars having tangs at their lower ends, of plates or shells mounted on said tangs, their edges abutting against and flush with outer ribs on said tangs, said plates having clasps at their upper ends and overlapping portions at their lower ends which meet and engage the ends

of said ribs, and being provided also with bosses projecting from transverse bars on the inner faces of the plates which span the space between said bars and engage inner shoulders on the lower ends of the tangs, the bosses receiving rivets, substantially as described. 15 20

In testimony whereof we have affixed our signatures in presence of two witnesses.

LOUIS SCHLESINGER.
LOUIS BOWMANN.
